TONE CONTROL

Harold Miller Lewis, Douglaston, N. Y., assignor
to Hazeltine Corporation

Application August 20, 1932, Serial No. 629,604

3 Claims. (Cl. 250—20)

This invention relates to sound-reproducing systems, and more particularly to means for automatically varying the tone of the reproduced sound.

5 In accordance with this invention, the tone of the reproduced sound, as, for instance, in an automatic volume control radio receiver, is varied automatically in such a manner that the high frequencies are reduced increasingly as the amplification is increased.

10 In a radio receiver, whenever the sensitivity is maximum, annoying hissing sounds of the higher audio frequencies are heard. With an automatic volume control receiver, whenever the 15 amplification is automatically increased, as, for instance, when tuning on either side of a broadcast signal, when tuning from station to station, or when receiving a weak signal, the hissing sounds are quite objectionable. Furthermore, the 20 static and noises of high audio frequencies, which are reproduced when the receiver is operating at maximum sensitivity and not tuned to any signal, are also quite objectionable.

25 In sound reproduction, as from a talking movie sound record, the passage of the record through the reproducer during the silent sequences with the amplifier set for maximum amplification results in the production of a disagreeable high-frequency hiss or scratch frequency sound.

30 It is the primary object of this invention to reduce the audio-frequency response to the higher frequencies whenever the sensitivity of the amplifier system is such as to produce these high audio frequencies to an objectionable extent.

35 It is a particular object of this invention to provide a radio receiver having an automatic volume control arrangement and an automatic tone control arrangement, each controlled by the intensity of the received carrier wave, so that 40 whenever the sensitivity of the receiver is greatly increased due to reception of signals of low intensity, the high frequencies in the output are correspondingly reduced; or, alternatively, whenever the receiver is tuned to powerful signals resulting in a decrease of sensitivity, the proportion 45 of high frequencies to low frequencies is increased.

These and further objects of the invention will 50 become apparent from the following description taken in connection with the accompanying drawings.

In accordance with this invention, means are provided for rectifying the received carrier wave, preferably after it has been amplified, to produce 55 a source of direct-current voltage which is pro-

portional to the received carrier wave. This voltage is then utilized to control the characteristics of a "tone control" so that the attenuation of the higher of the detected audio frequencies is varied in a predetermined manner as a function of the control voltage. 5

Where the receiver is of the superheterodyne type, the direct-current control voltage will preferably be obtained by rectifying the intermediate-frequency carrier rather than the original carrier-frequency current. In either case, however, the direct-current control voltage obtained is proportional to the received carrier wave amplitude, and its proportionality depends upon the type of detection used. For example, with linear detection, which is the type preferred, the direct-current voltage is almost directly proportional to the received carrier wave amplitude. 10 15

Although separate detectors may be used for providing the various control voltages, a single 20 detector may be made to function to yield the audio-frequency voltage, to provide the direct-current voltage for the automatic volume control, and to provide the direct-current voltage 25 for the automatic tone control.

The tone control may comprise any simple or complex impedance network provided only that one or more of its elements may be varied with voltage applied to give the control desired. The most simple arrangement contemplated is the one 30 in which resistance alone is varied, although a variety of circuits variable with voltage to control the frequency impedance characteristics of the tone control will occur to those skilled in the art. 35

In its preferred embodiment, this invention provides, as the variable resistance element of the tone control, a thermionic vacuum tube so arranged that the direct-current control voltage may be applied between the control grid and the 40 cathode to vary the plate-cathode resistance. If the control voltage is connected to make the grid more negative with respect to the cathode as the control voltage increases, the resistance of the tube will increase when the control voltage increases. A fixed capacity is connected in series with the plate of the vacuum tube as a shunt across the audio-frequency transmission system. With this arrangement, when no signal or a very weak signal is being received, the direct-current 45 control voltage is low and the resistance of the vacuum tube is low, thereby providing a shunt path consisting of capacity and resistance so proportioned as to by-pass the higher audio frequencies to whatever degree may be desired. 50 55

When a strong signal is being received, the direct-current control voltage is large, causing the resistance of the vacuum tube to become high, and thereby practically removing the shunt tone control 5 and permitting as perfect fidelity of reception as the receiver is capable of giving. Thus, the degree of elimination of the high frequencies will vary between these limits in a manner proportional to the amplitude of the received 10 carrier wave.

This invention will be better understood by consideration of the drawings, to which attention is now invited.

Fig. 1 is a schematic diagram of a radio receiver employing the automatic tone control of this invention;

Fig. 2a is a diagram of a manual tone control arrangement;

Fig. 2b is a diagram of a simple type of automatic tone control arrangement corresponding to the type shown in Fig. 2a;

Fig. 3 represents a superheterodyne radio receiver employing both automatic volume control and automatic tone control and utilizing a single 25 detector for producing the audio frequencies and direct-current control voltages;

Fig. 4 is a diagram giving the circuit arrangement of the receiver shown in Fig. 3;

Fig. 5 is a circuit diagram showing a super- 30 heterodyne receiver employing a separate detector for controlling the action of the tone control.

In Fig. 1, which is a schematic diagram of a radio receiver constructed in accordance with this invention, the antenna 10 and ground 11 are 35 connected to the radio-frequency amplifier 12, the output of which is connected to the detector 13. The detected output is connected through the tone control circuit 17, which will be described hereinafter, to the audio-frequency amplifier 14, 40 by which the detected signals are amplified to be reproduced by the loud speaker 15. A second detector 16, for controlling the automatic tone control 17, is connected in parallel with the first detector 13.

In operation, the modulated radio-frequency signal currents are collected by the antenna-ground system 10-11 and applied to the radio-frequency amplifier 12. The output of the amplifier 12 is applied to the two detectors 13 and 50 16. The detector 13 is arranged to produce the audio-frequency currents and supply them through the tone control 17 to the audio-frequency amplifier 14. The output of the audio-frequency amplifier 14 is connected to the loud 55 speaker 15. The tone control 17 controls the fidelity of the audio frequencies applied to 15 and has a frequency-attenuation characteristic, which is, as will be explained hereinafter, dependent upon the value of a direct-current potential applied as a control voltage from the detector 16. The detector 16 is supplied with radio-frequency 60 energy from the radio-frequency amplifier 12. This detector is adjusted to yield a steady value of direct-current voltage which is proportional 65 to the amplitude of the carrier wave applied to its input. It will thus be clear that when a strong signal is being received, the direct-current voltage output of the detector 16 is large, and hence 70 the frequency-attenuation characteristic of the tone control 17 is different from what it will be when a weak signal is received and the direct-current voltage output of the detector 16 is small. Thus, by virtue of the elements 16 and 17, the 75 quality of the signals delivered to the loud speak-

er 15 is made dependent upon the strength of the received signals.

In Fig. 2a the conductors 22-24 and 23-25 carry an audio-frequency current similar to that carried by the conductors between the detector 5 13 and the audio-frequency amplifier 14 of Fig. 1. The circuit in this figure shows a network which is similar to the manual tone control commonly employed in the present-day radio receiver for variably attenuating high audio frequencies. 10 This network, which is connected between the conductors 22-24 and 23-25, comprises a condenser 26 and a tapped resistor 27. The portion of the tapped resistor 27 which is connected in series with the condenser 26 between the conductors 22-24 and 23-25 is selected by means 15 of the tap switch 28. When the switch 28 is adjusted to include all of the resistor 27 in series with the condenser 26, the shunt path, comprising condenser 26 and resistor 27, has practically no effect, and the signals applied to the terminals 22 and 23 are freely transmitted to the terminals 24 and 25 without attenuation. When, however, the switch 28 is adjusted to include only a small portion of the resistor 27, a shunt path is provided which attenuates the voltage at the higher 20 audio frequencies applied to the terminals 22 and 23 more than it does that at the lower frequencies, depending upon the values of the condenser 26 and the portion of the resistor 27 then 25 included in the shunt path.

Fig. 2b illustrates the circuit arrangement of the tone control 17 of Fig. 1. In this circuit a shunt path, comprising the condenser 26 and the impedance of the tube 29, is provided between the 35 conductors 22-24 and 23-25, which connect the output of the detector 13 with the input of the audio-frequency amplifier 14. The frequency-attenuation characteristic of this shunt path is controlled by a variation of the grid voltage of the 40 tube 29. The grid voltage is determined by the output of the detector 16 of Fig. 1, as will be explained hereinafter, and when the potential applied to the terminals 31 and 32 is high and of the proper polarity to make 31 negative with respect to 32, the tube resistance is great and the attenuation effect of the tone control is negligible. When this potential difference between 31 and 32 is low, the resistance of the plate-cathode path 45 is low, and the higher frequencies are correspondingly attenuated.

The plate electrode and cathode of the tube 29 are supplied with appropriate operating potentials from sources which are not shown. The 55 impedance 30 is included between the plate-potential source and the plate electrode of the tube 29 in order to make the impedance of this parallel path from condenser 26 to the line 23-25 via the plate power supply higher than the impedance of the plate-cathode path of the vacuum tube, in order that the plate-cathode resistance may control the shunting of the high audio-frequency currents. A choke or any other filter offering a high impedance to all audio frequencies may be substituted for the resistance 30.

When connecting the tone control shown in Fig. 2b in the circuit at 17 of Fig. 1, direct-current voltage output of the detector 16 is applied to the terminals 31-32 and so poled as to make terminal 31 negative relative to terminal 32. Thus, 70 when a strong signal is received and a large direct-current voltage is developed in the output of the detector 16, the resistance of the tube 29 is high, and the audio-frequency signals developed in the output of the detector 13 pass without 75

attenuation to the audio-frequency amplifier 14. When, however, the incoming signals are weak, potential difference in the tone control input is so low that the tone control will effectively attenuate the higher audio-frequency currents.

While other types of tone control, which attenuate the audio frequencies in a different manner relative to the strength of the incoming signals, are contemplated and are within the scope of this invention, it will be clear that the form described, which attenuates the higher frequencies increasingly as the signals received become weaker, is a preferred form. The reason for this preference is that when weak signals are received, the receiver is generally operated at maximum sensitivity, and more static and extraneous noises are present, and their disturbing sound can be reduced by attenuating the higher audio frequencies more than the lower audio frequencies. This is particularly true when the receiver is equipped also with an automatic volume control, and the sensitivity is consequently automatically increased when weak signals or no signals at all are being received.

The arrangement shown in Fig. 3 illustrates a superheterodyne receiver employing an automatic volume control. In this figure, the parts similar to those shown in Figs. 1 and 2 are similarly designated. The output of the radio-frequency amplifier 12 is supplied to a modulator or first detector 19, which has also supplied thereto high-frequency oscillations produced by the oscillator 21 for the purpose of combining with the received radio-frequency signals and producing the intermediate-frequency signal currents, which latter currents are further amplified by an intermediate-frequency amplifier 20. The output of the intermediate-frequency amplifier 20 is supplied to the second detector 13'. The detector 13' takes the place of the two detectors 13 and 16 of Fig. 1, and its output is supplied to the tone control 17, which is similar to that of Fig. 1, and to the filter 18, the output of which controls the characteristics of the automatic tone control 17, as well as the amplification of the radio-frequency amplifier 12 and the intermediate-frequency amplifier 20. The currents passed through the automatic tone control 17 are amplified by the audio-frequency amplifier 14 and reproduced by the loud speaker 15. The oscillator 21 supplies to the modulator 19 energy of a frequency differing from the incoming signals of the carrier frequency by the intermediate frequency to which the intermediate-frequency amplifier is tuned. Thus, the modulator 19 supplies to the intermediate-frequency amplifier 20 the converted intermediate carrier and signal side bands representative of the audio frequencies being transmitted. The specific arrangements of the parts of the circuit just referred to include the usual superheterodyne arrangements and need not be further described.

The detector 13' is adjusted to develop the desired audio-frequency signal currents and to supply them through the tone control 17 to the audio-frequency amplifier 14. It also develops a direct-current voltage proportional to the received carrier wave and supplies it to the filter 18. The filter 18 is for the purpose of removing any audio or other frequency components from the output of the detector in order that the variable direct-current voltage shall be proportional to the amplitude of the carrier wave received. As is well known in the art of automatic volume control, the amplifying action of the vacuum tubes, composing the radio-frequency and inter-

mediate-frequency amplifying stages, is readily controlled by a direct-current voltage or bias applied to the control grids of the amplifier tubes. This biasing voltage is generally developed by rectifying the output of the intermediate-frequency amplifier and applying the resulting direct-current voltage or a proportionally-varying voltage obtained therefrom to the control grids. This voltage is so poled as to make the grids of the controlled amplifying tubes negative with respect to the cathodes thereof in proportion to the amplitude of the signal being received. The sensitivity of the receiver is reduced when the incoming signals are strong, but is increased when the incoming signals are weak.

In accordance, then, with this well-known method, the direct-current voltage output of the filter 18 is shown as being applied to the radio-frequency amplifier 12 and the intermediate-frequency amplifier 20 to control the gain of these amplifiers and hence provide automatic volume control. At the same time, however, the direct-current output of the filter 18 is applied to the tone control unit 17 to control its attenuation characteristics so that when weak signals are received, the higher audio frequencies are correspondingly attenuated. In this figure the tone control arrangement is assumed to be of the type shown in Fig. 2b.

The resulting attenuation of the higher audio frequencies, when receiving weak incoming carrier-frequency currents, is particularly desirable where the receiver has the automatic volume control illustrated. As is well known, when a radio receiver is equipped with an automatic volume control, the sensitivity of the receiver, which is low when receiving signals from a strong local station, increases rapidly as the receiver is tuned off resonance with the frequency of this station, and an undesirable hissing sound is heard on either side of the resonance point for every signal tuned through in operating the receiver. When, however, an automatic tone control is employed according to this invention, as in the system of Fig. 3, these high-frequency hissing sounds, occasioned whenever a strong carrier frequency is not present in the receiver, are reduced by the automatic attenuation of the higher audio frequencies.

Thus, the automatic tone control, in addition to its merits when operated in conjunction with a simple receiver as shown in Fig. 1, enhances and perfects the action of an automatic volume control receiver. Since the form of tone control of this invention is a potential-operated device and utilizes the direct-current potential already provided in receivers equipped with automatic volume control, very little more than the unit shown in Fig. 2b is required to be added in order to provide the automatic tone control.

In both Fig. 1 and Fig. 2 the tone control unit 17 has been shown as interposed in the line between the detector and the audio-frequency amplifier. It will be clear, however, that the tone control might equally well be inserted between the audio-frequency amplifier 14 and the loud speaker 15, or at any appropriate point in an amplifying system.

Fig. 4 represents diagrammatically a superheterodyne radio receiver similar to that shown in Fig. 3, and corresponding parts are designated by the same reference numerals. In this figure, however, the second detector, automatic volume control system, tone control system, and first audio-frequency amplifier are shown in detail.

The signal received by the antenna-ground system 10-11 and amplified by the radio-frequency amplifier 12 is converted into intermediate-frequency currents in the modulator 19, by 5 means of the heterodyning energy produced by the oscillator 21. The intermediate-frequency currents are amplified by the intermediate-frequency amplifier 20 and are applied to the vacuum tube 36 of the detector system 13' by means 10 of the transformer 33-34, the secondary 34 of which is tuned by the condenser 35.

The detector 13' is arranged to operate as a peak diode detector, as described in application of Harold A. Wheeler, Serial No. 526,857. In the 15 detector the audio frequencies and direct-current components are developed across the resistors 39 and 38, while currents of high or intermediate radio frequency are by-passed to ground by the condenser 37. The connections 40 and 41 supply 20 a direct-current potential, proportional to the received carrier wave, to the control grids of the vacuum tubes in the amplifiers 12 and 20, respectively. This permits the amplification of these 25 amplifiers to be automatically controlled to give substantially uniform output regardless of the signal input intensity. Resistors 44 and 45 serve as isolators to prevent audio and radio-frequency components present from feeding back into the circuits of units 12 and 20.

30 The connection 42 supplies the audio-frequency voltages developed by the detector 13' to the audio-frequency amplifier 14, where it is amplified and applied to the loud speaker 15. The first vacuum tube stage of the amplifier 14 is 35 shown in detail and includes the vacuum tube 50 having input circuit elements, including the isolating resistor 46 and condenser 48, for preventing high-frequency and direct current being impressed upon the input of the amplifier tube 50, 40 the volume control resistor 49, and biasing battery 52. The biasing battery 52 is by-passed by the condenser 51 connected between the end of resistor 49 and the cathode of the tube 50. Any desired amount of the voltage fluctuations existing 45 across the volume control resistor 49 may be impressed upon the grid of the amplifier tube 50 by means of the variable contact 49'. The output of the amplifier tube 50 includes the primary of the output transformer 53, the resistor 56, and 50 the high-potential source 54. The resistor 56 and the high-potential battery 54 are by-passed for audio-frequency currents by the condenser 57.

The audio-frequency output of the amplifier 55 tube 50 is supplied to the remaining part of the audio-frequency amplifier, represented at 58, by means of the transformer 53. The output of the amplifier 58 is reproduced by the loud speaker 15.

60 In shunt with the output path just described is included the tone control tube 29 and the condenser 26 constituting a shunt path between the plate and cathode of the amplifier tube 50. The tone control tube 29 is similar to that shown in 65 Fig. 2b and has its grid connected to the grid ends of resistors 38 and 39 by means of the connection 43, which latter includes a filter comprising the resistor 47 and condenser 47'. This provides a variable tone control arrangement in accordance 70 with the present invention.

Battery 54 supplies the plate potentials for the tubes 29 and 50. The connection between the plate of the tube 50 and the battery 54 is through the primary of the out-put transformer 53 and 75 the resistor 56. By-pass condenser 57 is con-

nected to the junction of the primary of transformer 53 and resistor 56 and to ground to bypass high-frequency currents. The plate supply to the tube 29 is through the resistor 30, and the portion of the battery 54 included in the plate circuit of tube 29 is by-passed for high-frequency currents by means of the condenser 53. The resistance of the resistor 30, included in the plate circuit of the tone control tube 29, is chosen to have a high impedance as compared with the 10 plate-cathode resistance of the tube 29.

It will be clear that when the grid of the tube 29 becomes increasingly negative with respect to its cathode, as when the direct-current potential developed across the resistor 39 and applied to 15 the grid of 29 through the connection 43 and the resistor 41 increases, the plate-cathode path of the tube 29 increases in resistance and the audio frequencies in the output of tube 50 are transmitted to the amplifier 58 with maximum fidelity. When little or no direct-current bias potential from the resistor 39 is applied to the grid of the tone control tube 29, the plate-cathode resistance of the tube 29 is low, and the higher 20 audio frequencies are readily by-passed in the output of the amplifier tube 50 through the condenser 26 and the tone control tube 29.

From the foregoing description it is clear that the circuit just described provides both automatic tone control and automatic volume control; that is, when no signal or a very weak signal is being received, little or no audio-frequency voltages exist across the resistors 38 and 39, and little or no direct-current potential is developed there. Hence no bias is furnished to the amplifier units 30 12 and 20, so that they function at maximum sensitivity. Furthermore, no bias is furnished to the tone control tube 29, so that the high frequencies are readily by-passed through the tone 35 control shunt circuit, and the high-frequency noise and static existing in the output and reproduced by the loud speaker 15 are reduced. With a strong incoming signal, direct-current potentials developed across the resistors 38 and 39, as supplied to the amplifier units 12 and 20, reduce 40 the sensitivity of the receiver, and at the same time the grid of the tone control tube 29 is biased more negative with respect to its cathode, thereby increasing the impedance of the tone control 45 path, and permitting all of the audio-frequency 50 currents to pass from the audio amplifier 50 to the amplifier 58 to be reproduced by the loud speaker 15 with substantially maximum fidelity.

Included in shunt with the output and tube-controlled tone control path of the amplifier 55 50 is a manual tone control circuit including the condenser 26' and the variable resistance 29'. By means of the resistor 29' the impedance of this path may be so adjusted that the proportion 60 of high frequencies by-passed in the output of the amplifier tube 30 may be increased or decreased so that the tone of the signals as reproduced by the loud speaker 15 may be adjusted to suit the listener's taste regardless of the sensitivity of the receiver.

In connection with the circuit of Fig. 4, it should be noted that the several isolating resistors 44, 45, and 47, together with condenser 47' and by-passing condensers which would normally be included in the amplifier units 12 and 20, 70 as is familiar to those skilled in the art, are the equivalent of the filter unit 18 shown in Fig. 3.

For convenience, the batteries 52 and 54 have been shown as a source of plate and grid potentials for the various tubes constituting this re- 75

- ceiver. It is understood, however, that in a commercial-form radio receiver these potentials would be supplied by the usual common power-supply system.
- 5 In Fig. 5 a receiver similar to that shown in Fig. 4 is illustrated, similar parts being designated by the same reference characters. In this figure, two detectors 13' and 16' are provided. The detector 13' is for the purpose of detecting 10 the audio-frequency signals and obtaining the automatic volume control effect and is connected in a manner similar to that in which detector 13' of Fig. 4 is connected, with the exception that the automatic volume control potentials are obtained 15 from the single grid resistor 38, the biasing potentials on the two amplifiers 12 and 20 being provided through the resistors 44 and 45, respectively. In this connection also, the audio frequency supplied to the audio-frequency amplifier 50 is taken from an intermediate point on the resistor 38.
- The auxiliary automatic tone control detector 16' is of the usual "diode" type and has its input supplied through connection 59 to the primary of 20 the output transformer of the intermediate-frequency amplifier 20. This connection includes the coupling condenser 60. A resistor 38' is included in the diode circuit and has its low-potential end connected to the grid of the tone control tube 29. The tone control tube 29 and its circuit are the same as in Fig. 4. Fig. 5 does not show a manual volume control, but may include one similar to that shown in Fig. 4 should it be so desired.
- 25 The usual cathode heating circuits are understood to be provided for the tubes shown in the circuits just described, the specific details of which constitute no part of the present invention.
- 30 40 What is claimed is:
1. In a radio receiver of the multi-stage vacuum-tube type, a radio-frequency amplifying section, a detector, an audio-frequency amplifying section, a tone control circuit including a voltage responsive variable impedance device for controlling the fidelity of said audio-amplifying section, circuit means for causing said detector to develop audio-frequency voltages in accordance 45 with the modulation of the carrier wave being received and a direct-current potential substantially proportional to the average amplitude of said carrier wave, means for applying said audio-frequency voltages to said audio-frequency amplifying section, and a plurality of means for applying said direct-current potential to said voltage responsive variable impedance device and to said radio-frequency amplifying section, whereby the fidelity and amplification of signals reproduced is controlled by the average amplitude of said carrier wave.
- 5 In a radio receiver of the multi-stage vacuum-tube type, a radio-frequency amplifying section, a detector, an audio-frequency amplifying section, a tone-control circuit including a voltage responsive variable impedance device for controlling the fidelity of said audio-amplifying section, circuit means for causing said detector to develop audio-frequency voltages in accordance 10 with the modulation of the carrier wave being received and a direct-current potential substantially proportional to the average amplitude of said carrier wave, means for applying said audio-frequency voltages to said audio-frequency amplifying section, and a plurality of means for applying said direct-current potential to said voltage responsive variable impedance device and to said radio-frequency amplifying section, whereby the fidelity and amplification of signals reproduced is controlled by the average amplitude of said carrier wave.
- 15 20 25 30 35 40 45
2. In a radio receiver of the multi-stage vacuum-tube type, a radio-frequency amplifying section, a detector, an audio-frequency amplifying section, a tone-control circuit including a voltage responsive variable impedance device for controlling the fidelity of said audio-amplifying section, circuit means for causing said detector to develop audio-frequency voltages in accordance 20 with the modulation of the carrier wave being received and a direct-current potential substantially proportional to the average amplitude of said carrier wave, means for applying said audio-frequency voltages to said audio-frequency amplifying section, means for applying said direct-current potential to said voltage responsive variable impedance device, whereby the fidelity of signals reproduced is controlled by the average amplitude of said carrier wave, and supplemental means for manually controlling the fidelity of the reproduced signal.
3. In a radio receiver adapted for receiving a modulated carrier wave, the combination of a detector for providing a source of voltage comprising an audio-frequency voltage variable in accordance with the modulation of the received carrier wave and a unidirectional voltage directly proportional to the average amplitude of the carrier wave supplied to said detector, means for separating said audio-frequency and said unidirectional voltages, means for utilizing said audio-frequency voltage to produce a signal, and a plurality of means for utilizing said unidirectional voltage separately to control the fidelity of said produced signal and to control the average amplitude of said supplied carrier wave.

HAROLD MILLER LEWIS.
